UNITED STATES PATENT OFFICE.

JOSEPH H. DILLS, OF SIOUX CITY, IOWA.

END-GATE FOR HOG-RACKS.

1,187,980.

Specification of Letters Patent. Patented June 20, 1916.

Application filed December 19, 1914. Serial No. 878,054.

To all whom it may concern:

Be it known that I, JOSEPH H. DILLS, a citizen of the United States, and a resident of Sioux City, in the county of Woodbury and State of Iowa, have invented certain new and useful Improvements in End-Gates for Hog-Racks, of which the following is a specification.

The present invention relates to end-gates for hog-racks.

The invention has for its primary object the production of an improved end-gate obviating the use of the usual tie-rods.

Another object of the invention is the production in a device of this class of improved operating means.

A still further object is the production of a device of this class inexpensive in production and highly efficient in operation.

With these and other objects in view, the invention, consisting in the construction, combination and novel arrangement of parts, will be fully understood from the following description, reference being had to the accompanying drawings forming a part of this application and in which like characters of reference indicate corresponding parts throughout the several views, of which,—

Figure 1 is a fragmentary perspective view of a hog-rack equipped with an end-gate constructed in accordance with the invention; Fig. 2 is an enlarged rear elevation of one side of the same, the bed-board and lock-keeper being shown in section and other parts cut away; Fig. 3 is a plan of Fig. 2; Fig. 4 is an enlarged perspective view of one of the flanged slides; Fig. 5 is a similar view of one of the grooved slide-retainers; Fig. 6 is an inner elevation of one of the lock-keepers; Fig. 7 is a rear elevation of the same; Fig. 8 is a vertical section of the same; Fig. 9 is an inner elevation of one of the lock-bolt-guides; Fig. 10 is a rear elevation of the same; and Fig. 11 is a vertical section of the same inclosing the lock-bolt.

Although I have illustrated and herein described the preferred embodiment of the invention, I would not be understood as being limited to the specific structure chosen for illustration, for various alterations and modifications in the details of construction and arrangement of parts may be made without departing from the spirit and scope of the invention as defined in the appended claim; and although the device of my invention finds its principal use as an end-gate

for a hog-rack, still it may be employed to great advantage as a gate for other closures or pens.

The gate is particularly adapted for brooding pens, inasmuch as it can be conveniently set at a position to permit the pigs to enter and leave the pen at will, and still prevent the exit of the sow.

The invention contemplates, broadly, a structure including an inclosure having an opening therein and a gate for the opening movable vertically thereof. The sides of the gate are armed with parts which slidably contact with members carried by the adjacent edges of the inclosure.

When employed upon a hog-rack, this novel construction prevents lateral movement of the sides of the rack and thus supplants the usual tie-rods. Novel operating means are also presented which securely lock the rack to the wagon-bed when the gate is closed.

Referring now to the illustrations, 12 represent the usual side members of the bed secured upon the customary cross-members, 13, by brace rods, 14. The floor boards are shown at 15. The rack includes the familiar longitudinal boards, 16, secured to posts, 17, adapted for inclosure by sockets, 18, mounted on the side members of the bed.

The end-gate comprises horizontal bars, 19, secured to the forward side of uprights, 20. The sides of the gate are clad with flanged strips, preferably T-irons, the edges of the webs of which, 21, embrace the ends of the cross-bars 19 and are suitably secured to the latter as by straps or plates, 22, riveted to the irons and cross-bars. The flanges, 23, of the T-irons are slidably engaged within grooves, 24, in strips, 25, firmly secured to the inner sides of the rack bars 16. The uppermost ends of the flanges 23 are bent outwardly, as at 26, to engage the ends of the channel strips and support the gate a sufficient distance above the floor whereby its operation will not be obstructed by accumulations of material upon the floor.

On the rear of the end-gate is a lever, 27, fulcrumed near its lower end upon a suitable bearing, 28, mounted between the two lower cross-bars. Oppositely disposed lateral rods, 29, are secured to the lever on opposite sides of its pivotal point, and are slidably engaged within guide blocks, 30, resting upon the lower cross-bar and provided with ears 31, which are secured to the opposite

sides of the uprights 20. The said rods terminate in squared heads or lock-bolts, 32, between which and the inner ends of the guide blocks are interposed compression-springs, 33, tending to force the bolts outwardly at all times. (Figs. 2 and 11.) The lock-bolts are received by suitable keepers, embedded in the side members of the rack bed and preferably comprising plates, 34, having side flanges, 35, disposed transversely of the rack and spaced sufficiently to admit the lock-bolts. The plates are formed with inner shoulders, 36, engaged by the lock-bolts to prevent upward movement 15 of the gate. The keepers are secured within mortices, 37, in the bed members by bolts, 38, which pass through the bed members and serve also to secure the braces, 14. A sharpened lug, 39, depending from the plate 20 of the lock-keeper is adapted to be driven into the bed member of the rack. The flanges of the keepers extend a distance above the bed members and engage notches, 40, in the lower inner corners of the channeled strips 25, thus aiding in preventing inward displacement of the sides of the rack. The lever 27, preferably of spring material, tends to spring rearwardly and slidably engages the forward side of a horizontal guide 25 strip, 41, mounted in spaced relation to and upon one of the cross bars and is formed with a rear offset, 42. By virtue of this construction it is clear that the lock-bolts may be withdrawn by movement of the lever and thus permit vertical movement of the end-gate. The gate is supported in open position by engagement of the lock-bolts within depressions, or pockets, 43, in the upper portions of the grooved slides 25.

30 If desired to leave the gate unlocked, as

when removing or mounting the gate, the lever is moved sufficiently to spring into the off-set portion 42 of the lever guide.

It will be observed that the side members of the rack are securely locked to the wagon bed when the off-set ends of the T-irons are in engagement with the grooved strips and the lock-bolts are engaged within their keepers.

Having thus described my invention, what I claim as new and desire to secure by Letters Patent, is,—

The combination with a wagon-bed having side-boards, and an inclosure mounted upon the wagon-bed and including side members and an end-gate, of channeled strips secured to the side members, flanged uprights secured to the sides of the end-gate and slidably inclosed by the channeled strips, inwardly-yieldable lock-bolts mounted on the end-gate and extending beyond the side edges thereof, lock-bolt keepers embedded in the side-boards and including plates having side flanges and shoulders to engage the lock-bolts to prevent vertical movement of the end-gate, the flanges being extended above the side-boards, the lower edges of the outer sides of the channeled strips being supported by the plates and the sides of the channeled strips being cut away to rest upon the flanges of the plates, and means for withdrawing the lock-bolts.

In testimony whereof I have hereunto set my hand in presence of two subscribing witnesses.

JOSEPH H. DILLS.
